US00D728105S

(12) **United States Design Patent** (10) **Patent No.:** **US D728,105 S**
Kim et al. (45) **Date of Patent:** **** Apr. 28, 2015**

(54) **COMPUTER TOMOGRAPHY APPARATUS**

(71) Applicant: **Samsung Electronics Co., Ltd.**, Suwon-Si, Gyeonggi-Do (KR)

(72) Inventors: **Yun-Su Kim**, Seoul (KR); **Euisik Kim**, Seoul (KR); **Yeonmoo Chung**, Seoul (KR)

(73) Assignee: **Samsung Electronics Co., Ltd.**, Gyeonggi-Do (KR)

(**) Term: **14 Years**

(21) Appl. No.: **29/482,731**

(22) Filed: **Feb. 21, 2014**

(30) **Foreign Application Priority Data**

Aug. 28, 2013 (KR) 30-2013-0044199

(51) **LOC (10) Cl.** **24-01**

(52) **U.S. Cl.**

USPC **D24/158**

(58) **Field of Classification Search**

USPC D24/158-161, 185, 186; 378/4, 15, 17, 378/21, 23-27, 62, 68, 196-198; 600/407, 600/409, 410, 415, 421, 422, 425

See application file for complete search history.

(57) **CLAIM**

We claim, the ornamental design for a computer tomography apparatus, as shown and described.

DESCRIPTION

FIG. 1 is the front perspective view of a computer tomography apparatus showing my new design;
FIG. 2 is a front elevation view thereof;
FIG. 3 is a rear elevation view thereof;
FIG. 4 is a side elevation view thereof;
FIG. 5 is another side elevation view thereof;
FIG. 6 is a top plan view thereof; and,
FIG. 7 is a bottom plan view thereof.
